UNITED STATES PATENT OFFICE.

JOSEPH A. PUTT, OF CANTON, OHIO.

INCANDESCENT VAPOR-BURNER.

SPECIFICATION forming part of Letters Patent No. 623,738, dated April 25, 1899.

Application filed January 9, 1899. Serial No. 701,667. (No model.)

To all whom it may concern:

Be it known that I, JOSEPH A. PUTT, a citizen of the United States, residing at Canton, in the county of Stark and State of Ohio, have 5 invented certain new and useful Improvements in Incandescent Vapor-Burners; and I do hereby declare that the following is a full, clear, and exact description of the same, reference being had to the annexed drawings, 10 making a part of this specification, and to the figures of reference marked thereon, in which—

Figure 1 is a side elevation showing the different parts of the present invention properly 15 arranged. Fig. 2 is a vertical section.

The present invention has relation to incandescent vapor-burners; and it consists in the different parts and combination of parts hereinafter described, and particularly pointed out in the claim.

Similar numerals represent corresponding parts in both figures of the drawings.

In the accompanying drawings, 1 represents the body, which is substantially of the form shown, and, as shown, it is provided with the ordinary supply-pipe 2. The fuel enters the passage 3 and is conveyed by pressure to the cross-passage 4 and thence downward through the passage 5, where it enters the passage 6, 20 from whence it is conveyed through the tip 7. In use the lower portion of the body 1 is heated in the ordinary manner, by means of which the gasolene is converted into gas, after which it escapes through the tip and into the tube 8, which tube is extended upward and its top or upper end covered with the wire-gauze 9.

For the purpose of supporting the chimney 10 the flange 11 is provided, which flange is 25 connected to the body in any convenient and well-known manner, and above the flange 11 and within the chimney 10 is located the cylinder 12, which cylinder is formed of greater diameter than the pipe or tube 8, by which arrangement a chamber, such as 13, is provided and is located around the pipe 8, except at the point where the passages 3, 4, and 5 are formed. The cylinder 12 is formed of greater diameter than the tube 8, by which arrangement the chamber 13 is formed, which is located around the tube 8, except at the place where the passages 3 and 5 are located, and

is for the purpose of holding in proper position the gauze 9 and at the same time providing a means for heating the gas to a greater 55 degree by inclosing the top or upper end of the tube 8.

After a sufficient amount of gas has been generated by heating the bottom or lower end of the body 1 the gas is ignited at a point just 60 above the wire-gauze 9 by applying a match to one side of the mantle 14, after which the plug or screw 15 becomes heated by the flame of the gas. For the purpose of better heating the screw or plug said screw or plug is 65 provided with the lateral head 16, which head is extended over the wire-gauze 9, as illustrated in the drawings. The plug or screw 15 is extended downward to a point where it will form the upper side of the passage 4, by 70 which arrangement said passage will become heated, or, in other words, the screw or plug 15, by reason of the lateral head 16 being located over the wire-gauze 9, will be located in the flame of the burning gas, thereby bringing 75 said screw or plug to a high degree of heat, by which arrangement the gasolene will be converted into gas at the time it is brought under the heated screw or plug 16.

For the purpose of regulating the flow of 80 gas the needle-pointed screw 17 is provided and is operated in the ordinary manner.

It will be understood that the screw or plug 15 should be formed of copper or like material, for the reason that it is to be used for the 85 purpose of conducting heat to the passage 4. For the purpose of supplying air the air-passages 18 are provided, which air-passages are located at the bottom or lower end of the tube 8 just above the tip 7, and for the purpose 90 of protecting the air-passages 18 the hood 19 is provided, which hood is located and arranged substantially as shown in the drawings.

It will be understood that when the mantle 95 14 is brought in the proper position the plug or screw 15 will be located within the mantle, thereby bringing said plug or screw in proper position, for the purpose above described.

Having fully described my invention, what 100 I claim as new, and desire to secure by Letters Patent, is—

In an incandescent vapor-burner, the combination of the body 1, provided with a sup-

ply-pipe, passages 3, 4, 5 and 6, a tip located at the bottom of the tube 8, air-passages located in the tube 8 above the tip, the cylinder 12 located around the upper end or portion of tube 8, the gauze 9 located over the tube 8, and the plug 15 provided with the head 16, substantially as and for the purpose set forth.

In testimony that I claim the above I have hereunto subscribed my name in the presence of two witnesses.

JOSEPH A. PUTT.
